ELECTRICAL CONNECTOR DEVICE

Edgar E. Marquis, Brookfield, Conn. (Rte. 1, Flat Swamp Road, Newton, Conn.), and James A. Marquis, 6 Young Place, Danbury, Conn.

Filed May 1, 1962, Ser. No. 191,535

2 Claims. (Cl. 339—118)

This invention relates to electrical connection devices, and more particularly to a female connector of the type employing fluent material as a means for establishing an electrical contact between the connector and a male connector tip inserted into the device.

A main object of the invention is to provide a novel and improved female connector which may be employed in a number of different ways, for example, as a rotatable connector, the female connector device being relatively simple in construction, providing an efficient electrical connection with very low contact resistance, and being arranged so that it cannot be readily damaged.

A further object of the invention is to provide an improved female electrical connector device which is inexpensive to manufacture, which may be made in very small sizes, which provides an efficient low-resistance electrical contact with a cooperating male connector element and which is highly resistant to shock and vibration.

A still further object of the invention is to provide an improved female electrical connector device which is extremely versatile in its applications, which has a controllable insertion and withdrawal force which makes it especially suitable for use with multi-pin connector units, and which is protected against damage by the insertion of oversized pins therein.

Further objects and advantages of the invention will become apparent from the following description and claims, and from the accompanying drawings, wherein:

FIGURE 1 is an end elevational view of an improved female connector unit constructed in accordance with the present invention.

FIGURE 2 is a longitudinal vertical cross sectional view taken substantially on the line 2—2 of FIGURE 1.

FIGURE 3 is a longitudinal vertical cross sectional view taken through a modified form of female connector element constructed in accordance with the present invention.

FIGURE 4 is a longitudinal vertical cross sectional view taken through a still further modification of a female connector unit according to this invention.

FIGURE 5 is a longitudinal cross sectional view taken through another form of female connector unit according to the present invention.

FIGURE 6 is a longitudinal vertical cross sectional view taken through the unit of FIGURE 5 but showing a male connector tip inserted therein.

FIGURE 7 is a longitudinal vertical cross sectional view taken through an electrical connector of the military type provided with improved female connection means according to this invention.

FIGURE 8 is a fragmentary side elevational view partly in longitudinal cross section of still another form of female connector element according to the present invention, shown with a male contact tip received therein.

Referring to the drawings, and more particularly to FIGURES 1 and 2, 11 generally designates an improved female connector assembly according to the present invention. The assembly 11 comprises a generally tubular metallic main body 12 having the longitudinally extending cylindrical cavity 13 which is open at one end of the body 12. The opposite end of the body 12 is formed with the stem 15 having the integral soldering lug 16 adapted to be permanently connected to the end of a lead

wire or other electrical conductor, as by soldering, or the like.

Secured on the main body 12 is a sleeve 17 of suitable material, such as brass or plastic, the sleeve member 17 being formed at its forward end with an inwardly projecting annular retaining rim or flange 25 formed with the inwardly converging, generally frusto-conical opening 19 leading to the cylindrical bore 20 of the annular rim 25.

Disposed in the sleeve member 17 and retained between the rim 25 and the open end of body 12 is an annular sealing member 22 of resilient deformable material, such as neoprene, rubber, or the like.

As shown in FIGURE 2, the annular member 22 is integrally formed with an inwardly tapering end portion 23 which projects axially into the bore 13, the rim of body 12 being provided with an inward bevel adjacent to portion 23 to provide clearance therefor. The member 22 is formed with the cylindrical axial bore 18 which leads to the conical, inwardly tapering bore portion 26 of member 23, said member being formed at its end with a slit 27 which is normally closed, whereby the member 22 normally seals off the cavity 13. A quantity of electrically conductive fluent material 28 is provided in the cavity 13, said material comprising any suitable electrically conducting liquid, powder or paste, such as mercury, electrolyte, or the like.

The sealing member 22 is adapted to yieldably receive a male connector tip, the tip being insertable through the slit 27 into the cavity 13 to conductively engage the fluent material 28, whereby to establish an electrical connection between said tip and the metal main body 12.

As shown in FIGURE 2, the bore 20 of the restraining member 18 is preferably greater in diameter than the maximum inside diameter of the bore of the sealing member 22, namely, than the inside diameter of the cylindrical bore 18. Thus, the bore 18 serves not only as a guide and stabilizer for a male contact pin, but cooperates with the bore 20 to prevent the insertion of an excessively oversize pin, thus preventing damage to the female connector unit from the use of such a pin.

FIGURE 3 shows a form of the invention employed for use as a miniaturized female connector. Thus, the miniaturized device, designated generally at 29 comprises the metal body 30 formed with the connection bore 31 adapted to receive and be permanently connected to the end of a lead wire, or the like, by soldering, or by similar means. The body 30 is formed at its opposite end with a stud portion 32 on which is secured the tubular sleeve 33 of suitable material, such as brass or plastic. Secured in the open end of the sleeve 33 is the inwardly convergent, generally conical resilient deformable sealing member 34 formed at its inner end with the normally closed but yieldable slit 35, the sealing member 34 being adapted to yieldably receive a male connector tip and to allow the tip to be received in the bore of the sleeve member 33 and to make electrical contact with a mass of electrically conducting fluent material 28 contained in said bore. Thus, electrical contact is established between the male connector tip received in the sleeve 33 and the metal connector body 30 through the conductive fluent material 28.

Referring now to FIGURE 4, another form of female connector according to the present invention is illustrated. The connector is designated generally at 36 and comprises a generally tubular metal main body 37 formed at one end with the stud portion 15' which terminates in the connection lug 16' adapted to be employed for receiving the end of a lead wire, or similar electrical conductor and to be permanently secured thereto, by soldering, or the like.

The opposite end of the body 37 is formed with the convergent rim 38 in which is secured a rigid retaining

ring 39 having the cylindrical end bore 20' and the frusto-conical end bevel 19'. The body 37 is provided with the generally cylindrical main bore 40 which is somewhat enlarged adjacent the retaining ring 39, as shown at 41. Secured in the enlarged bore portion 41 is a substantially annular resilient deformable sealing member 42 having an inwardly tapering frusto-conical end portion 43 received in the bore 40. The member 41 is provided with the cylindrical main bore 44 which communicates with the inwardly convergent bore portion 45. The end of the conical portion 43 is formed with the normally closed yieldable slit 46 which normally seals off the interior cavity 40 of member 37. A quantity of electrically conductive fluent material 28 is provided in the cavity 40. Thus, a male connector tip is adapted to be inserted through the member 42 into the cavity 40, the slit 46 being yieldable to allow the tip to pass therethrough, whereby the tip comes into electrical contact with the electrically conducting fluent material 28, thus establishing an electrical connection between the male connector tip and the female connection device 36.

As in the form of the invention illustrated in FIGURES 1 and 2, the bore 20' is preferably larger in diameter than the inside bore 44 of the member 42, for the same reasons as given above in connection with the embodiment of FIGURES 1 and 2.

Referring to the form of the invention shown in FIGURES 5 and 6, the female connector element designated at 47 in said figures comprises an electrically conductive metal main body 48 formed with a stud portion 49 adapted to be soldered, or otherwise permanently connected to a lead wire or other electrical conductor. Secured on the end of the member 48, which is frusto-conical in shape, is a sleeve 50 of suitable rigid material, such as brass or other rigid material, formed at its end with the integral inwardly projecting annular retaining flange 51 having a cylindrical bore 52. Secured in the inner bore 53 of the sleeve 50 adjacent to the flange 51 is a generally annular resilient deformable sealing member 54 of rubber, neoprene, or the like having the conical, inwardly convergent bore 55 leading to the yieldable, normally closed end slit 56. Disposed in the cavity 53 of the sleeve 50 is a mass of conductive fluent material 28. As shown in FIGURE 6, the tip of a male connector member 57 is engageable through the resilient deformable member 54, the slit 56 being yieldable, whereby the tip 57 may pass into the cavity 53 and come into contact with the electrically conducting fluent material 28, thus establishing an electrical connection between the tip 57 and the conductive main body 48.

FIGURE 7 shows an electrical connection assembly 60 of the military type which includes an annular resilient deformable connector-mounting inner body 61 in which is secured a female connection element 62 constructed in accordance with the present invention. The connection element 62 comprises a conductive main body 63 having an end bore 64 in which is adapted to be secured the end of a lead wire, or similar electrical conductor, in a permanent manner, as by soldering, or the like. A rigid plastic sleeve 65 is secured on the reduced stud element 67 formed on the body 63 opposite the cavity 64, the sleeve being formed at its end with the inwardly projecting retaining flange 68. A resilient deformable member 42, similar to that illustrated in FIGURE 4, is secured in the sleeve 65 adjacent the flange 68, and a mass of fluent conductive material 28 is provided inside the sleeve 65 so as to be engageable with the tip of a male connector element inserted through the resilient deformable sealing member 42. This establishes electrical contact between the male connector element and the body 63 of the female receptacle unit 62.

FIGURE 8 illustrates another form of female connector element according to the present invention, designated generally at 70. The female connection unit 70 com-

prises the generally tubular rigid metal main body 71 integrally formed at one end with a connection stem 72 which may be suitably connected to a lead wire or other electrical connector in a permanent manner, for example, as described in connection with FIGURES 1 to 4. Secured in the opposite end of the tubular body 71 is an annular rigid metal restraining bushing 73, and secured inside the tubular member 71 adjacent the bushing 73 is a generally annular resilient deformable sealing member 74, which may be similar to the sealing member 54 shown in FIGURES 5 and 6. A body of electrically conducting fluent material 28 is provided in the cavity 75 of member 71, said fluent material establishing electrical contact between the tip of a male connector element 76 inserted through bushing 73 and sealing member 74 into the cavity 75, and the body 71, as illustrated in FIGURE 8. The bushing 73 is formed with the frusto-conical end bore portion 77 to facilitate the insertion of the tip 76 into the female connector device 70.

As will be readily apparent, in any of the forms of the invention above described, the male tip may rotate relative to the female connector without interfering with the efficiency of the electrical connection provided by the electrically conductive fluent material 28, so that the device of the present invention may be employed for establishing electrical connections between a pair of relatively rotatable bodies.

While certain specific embodiments of an improved female connector assembly have been disclosed in the foregoing description, it will be understood that various modifications within the spirit of the invention may occur to those skilled in the art. Therefore, it is intended that no limitations be placed on the invention except as defined by the scope of the appended claims.

35 What is claimed is:

1. A female connector comprising a generally tubular conductive main body open at a first end thereof, an axial connection stem integrally formed at the other end of said main body to permanently connect said other end to an electrical conductor, a rigid sleeve secured on said main body and being integrally formed with an inwardly projecting retaining flange located adjacent said open first end of the main body and having a cylindrical axial bore, an annular sealing member of resilient deformable material disposed and retained between said flange and the rim of said open first end of the main body, said sealing member having an inwardly tapering hollow end portion which projects axially into the bore of said main body, said hollow end portion having a normally closed end slit which normally seals off the interior of said main body, and a mass of electrically conductive fluent material in the interior of said main body, said sealing member being adapted to yieldably receive a male connector tip and to admit said tip through said slit into said cavity and into conductive engagement with said fluent material.
2. A female connector comprising a generally tubular conductive main body open at a first end thereof, an axial connection stem integrally formed at the other end of said main body to permanently connect said other end to an electrical conductor, a rigid sleeve secured on said main body and being integrally formed with an inwardly projecting retaining flange located adjacent said open first end of the main body and having a cylindrical axial bore, an annular sealing member of resilient deformable material disposed and retained between said flange and the rim of said open first end of the main body, said sealing member having an inwardly tapering conical hollow end portion which projects axially into the bore of said main body, said hollow end portion having a normally closed end slit which normally seals off the interior of said main body, and a mass of electrically conductive fluent material in the interior of said main body, said sealing member being adapted to yieldably receive a male connector tip and to admit said tip through said slit into said cavity and into conductive engagement with said fluent material,

said retaining flange having an inner bore greater in diameter than the maximum inside diameter of said sealing member.
